Inventor:

WILLIAM P. CRAMP.

By

William P. Cramp

Attorney:

UNITED STATES PATENT OFFICE.

WILLIAM P. CRAMP, OF PHILADELPHIA, PENNSYLVANIA.

SLIDING-DOOR HANGER.

Application filed February 9, 1927. Serial No. 166,904.

This invention, generally stated, relates to door hangers and has more especial relation to that class of door hangers used in connection with partition doors employed, 5 in class rooms, Sunday school rooms, and similar places.

The leading object of the present invention resides in the provision of means whereby the bolt may be easily and conveniently 10 removed from its hangers irrespective of the position of the door.

A further object is to provide hinged connections for the door hangers in order that the door may be moved laterally with 15 respect to its track if occasion demands.

A still further object is to provide a cupped casing for the door top in order to accommodate and conceal the hinged part.

Still another object is to provide a bolt 20 attachment for said hinged and cupped parts in which nuts and like attachment parts are eliminated.

Other and further objects reside in the provision of general details of construction 25 and arrangement and combination of parts for attaining the results sought by the foregoing objects.

The invention consists of the novel construction hereinafter described and finally 30 claimed.

The nature, characteristic features and scope of the invention will be more fully understood from the following description taken in connection with the accompanying 35 drawings forming part hereof, and in which:

Fig. 1, is a fragmentary view, principally in longitudinal section, illustrating a door hanger in operative position.

Fig. 2, is a view in section taken upon 40 the line 2—2 of Fig. 1; and

Fig. 3 is a view in section of the hanger detached.

For the purpose of illustrating my invention I have shown in the accompanying 45 drawings one form thereof which is at present preferred by me, since the same has been found in practice to give satisfactory and reliable results, although it is to be understood that the various instrumentalities 50 of which my invention consists can be variously arranged and organized and that my invention is not limited to the precise arrangement and organization of the instrumentalities as herein shown and described.

One of the chief difficulties with hanging

door attachments is that there is little head room between the door top and the under side of the rail upon which guide rollers move. Thus, in unloosening the attaching bolts the latter contact with the underside of 60 said rail. This necessitates moving the door to the extreme end of the rail so that proper access to the bolts may be had. This difficulty I overcome with the structure about to be described, only a portion of the door and rail or track being shown for illustrative purposes. In the drawings the reference numeral 1 designates a door the upper or top edge being cut away to receive a metal cup 2 the flanges 3 of which are flush 70 with the door top and are secured thereto by screws 4. The bottom of member 2 is provided with a screw-threaded aperture 5 within which is screwed the bolt 6. The latter is loosely passed through the hole 7 75 of pivotal block 10, the head 8 of the bolt being accommodated in the slot 9 in the top of said block. The block is of generally rectangular shape and is made of metal. The block 10 is provided with trunnions 80 11—12 arranged between a pair of hangers 13—14 and having bearings therein. In turn the hangers are carried by a plurality of rollers 15 which travel upon track 16 and support the door 1. It is thus apparent 85 that when the bolt is freed from member 2 it is possible to tilt the block 10 sufficiently so that the vertical axis of the bolt instead of being in alignment with rail or track axis is at an angle thereto, so the bolt may be 90 readily removed from block 10 irrespective of the position of the door. Thus, the hanger and door may be very conveniently and quickly uncoupled when occasion requires. Further, by my construction nuts, washers, 95 pins and other fastenings are eliminated, the bolt 6 being the only fastening medium required.

What I claim is:

1. In a structure of the character stated, 100 a sliding door the top of which is cutaway, a dished member fitted to said cutaway portion and having a threaded opening in its bottom, a wheeled member arranged to travel upon a track, a pair of independent 105 pendant arms carried by said wheeled member, each arm having a single bearing and provided with a pair of wheels, a tiltable, solid block having pintles arranged in said bearings and having an opening in align- 110

ment with said threaded opening, and a bolt extended through said block and directly engaging said threaded opening.

2. In a structure of the character stated, 5 a sliding door the top of which is cutaway, a dished member of substantially U-shaped cross section fitted to said cutaway portion and having a threaded opening in its bottom, a wheeled member arranged to travel 10 upon a track, a pair of pendant arms car-

ried by said wheeled member, each arm having a single bearing and carrying two wheels, a titable block having pintles arranged in said bearing and having an opening in alignment with said threaded opening, said block having a slotted top, and a bolt extended through said block and engaging said threaded opening, the head of said bolt being accommodated in said slot. 15

WILLIAM P. CRAMP.
